UNITED STATES PATENT OFFICE.

JOSEPH F. LAMB, OF NEW BRITAIN, CONNECTICUT, ASSIGNOR TO LANDERS, FRARY & CLARK, OF NEW BRITAIN, CONNECTICUT, A CORPORATION.

METHOD OF FORMING AND ATTACHING BOLSTERS TO CUTLERY IMPLEMENTS AND THE BOLSTER-BLANK THEREFOR.

1,136,603.

Specification of Letters Patent. Patented Apr. 20, 1915.

Application filed June 3, 1914. Serial No. 842,623.

To all whom it may concern:

Be it known that I, JOSEPH F. LAMB, a citizen of the United States, residing at New Britain, in the county of Hartford and State 5 of Connecticut, have invented certain new and useful Improvements in the Methods of Forming and Attaching Bolsters to Cutlery Implements and the Bolster-Blanks Therefor, of which the following is a specification.

10 My invention relates to the method of forming and attaching bolsters to cutlery implements and the blank therefor, and the objects of my improvement are simplicity and economy in construction and the production of a superior article, the process being especially adapted for producing knives and analogous flat bladed implements with a neat finish at the junction of the flat blade and attached bolster.

20 In the accompanying drawing:—Figure 1 is a side elevation of a knife less the handle, as made by my method. Fig. 2 is an enlarged side elevation of the heel and shank portion of the knife blade. Fig. 3 is a side 25 elevation of the bolster blank. Fig. 4 is a sectional view of the same on the line $\alpha\alpha$ of Fig. 3. Fig. 5 is an end view of the said blank showing the right hand end of Figs. 3 and 4. Fig. 6 is a side elevation of the 30 tang. Fig. 7 is a like view of a modified form of the tang. Fig. 8 is an enlarged 35 sectional view of the blade, bolster and tang on the line yy of Fig. 1, the outer end of the blade and tang being broken off. Fig. 9 is 40 a longitudinal section of the same on a plane at a right angle to the plane of Fig. 8. Fig. 10 is a sectional view on the same scale as Fig. 2 of the blade on the line zz of Fig. 1, looking toward the bolster. Fig. 11 is a 45 side elevation showing a modified form of tang.

This invention is in the nature of an improvement in the art of forming and securing bolsters to implements of cutlery according to my Patent No. 1,059,673, April 22, 1913. My present improvement is more particularly designed for knives or analogous flat bladed implements made from sheet metal. I prefer to form the said 50 blades 11 with a short shank 12 and a narrower central projection 13 that extends centrally from the end of the said shank. The edges of the shank may be inclined a little as shown in Fig. 2 so as to make the shank

of a dove-tail form. The shank is also perforated as at 14. The bolster blanks, Figs. 3, 4 and 5, may be first turned of a round form in end view and of the general contour of a finished bolster in side view. That is to say they are formed with a grooved neck 55 15, a narrow rib 16 at the smaller end and a thicker and larger head 17 at the other end. This head may be first made in the form of a short cylinder and then slabbed off or truncated on two sides as at 18, Figs. 60 3 and 4, so as to narrow the said head at what are to be the two broad sides 19 of the finished bolster, while at the ends 20 of the bolster which come at the edges of the 65 blade this head is of full thickness as most 70 clearly shown in Figs. 1 and 3. The head 17 of the bolster blank is slotted across the end midway between the two truncated faces 18 as shown by slot 21, Figs. 4 and 5. The 75 smaller end of the bolster blank is drilled 75 centrally as at 22, the bottom of the slot 21 at the larger end, and the largest diameter of the drill hole meeting each other so that the full diameter of the drill hole opens into the said slot, and without making any enlargement of the slot at the blade end of the 80 bolster. The depth of the said slot is fully equal to the length of the blade shank longitudinally of the blade while the diameter of the round head in which the said slot is 85 formed is preferably a little in excess of the width of the said shank. The projection 13 that extends centrally from the end of the shank is of a width to correspond with the diameter of the hole 22 in the shank end of 90 the blade within the bolster blank. I prefer to provide the bolster and blade with a separately formed round tang 23, but in case a 95 flat tang is desired, I extend the central projection of the blade shank, so as to obtain in addition to the dowel pin or tenon function an integral tang 13^a as shown in the modification Fig. 11.

The separately formed round tang 23 may be formed of round wire and grooved or 100 headed so as to form a holding shoulder 24 near one end. The said shoulder as formed in a groove is shown in Fig. 6 and the modified form of shoulder 24^a as formed by heading is shown in Fig. 7. Inasmuch as 105 the body of the tang should be of a certain size the modified form of tang will require a larger hole in the bolster blank to receive

the same. The diameter of the hole 22 in the bolster blank is such as to receive the shouldered end of the tang.

The separately formed blade, bolster and tang as hereinbefore described are assembled by inserting the shank and central projection of the blade into the slot and central hole of the bolster blank and the shouldered end of the tang is inserted in the round hole 14 at the other end of the bolster, preferably with the ends of the said projection and tang abutting each other. They are then secured together by pressing the bolster blank in dies, at the same time changing the round form of the bolster blank to an oval form and forcing the metal thereof solidly over the opposite edges of the shank as at 25, Fig. 9, into the hole 14 and around the inclosed shouldered end of the tang as shown in Figs. 8 and 9, thereby firmly securing the said three parts together. There is no substantial difference in the assembling and securing processes whether one form or the other of the separately round tang is employed but the tang which is shouldered by the heading operation is less expensive to make. A round tang is the most desirable on account of the convenience of securing a handle thereto and a separately formed tang is more economical than is a flat tang formed integral with the blade.

When a tang formed as shown in Fig. 11 is employed there is no change made in the bolster blank and the blade and bolster blank are assembled in precisely the same way except for the increased length of the central projection of the shank. The bolster is secured thereon by pressure in dies, forcing the metal solidly over the opposite edges of the shank and into the hole 14 as hereinbefore described and shown in Figs. 8 and 9, while the metal of the bolster blank will be forced upon the flat tang solidly enough for all practical purposes.

By my improvement I am enabled to attach a separately formed bolster blank and a flat blade by an inexpensive process and at the same time secure them beyond accidental displacement or loosening, and also what is of equal if not more importance, with such a firm and compact union for the whole width of the blade that the said union is almost imperceptible and would never be noticed by an ordinary observer. I am also enabled to provide the desirable round tang with a flat blade at a small cost.

I claim as my invention:

1. That improvement in the art of forming and securing bolsters to cutlery implements which consists in separately forming a flat blade with a short shank and a central projection therefrom, and a bolster blank having a grooved neck, a rib at one end of said neck, a transversely slotted head at the other end, and a central hole through

the ribbed end that terminates within the said slotted head, assembling the said bolster blanks on the shank of the said blade and positioning the same therein by having the said central projection enter the said round hole, with the flat shank filling the said slotted head at the outer end of the said hole, and then securing the bolster thereon by pressing the bolster in dies.

2. That improvement in the art of forming and securing bolsters to cutlery implements which consists in separately forming a flat blade, a round tang and a bolster blank slotted and drilled at its opposite ends to receive said blade and tang, assembling the said blade and tang within the opposite ends of the said bolster blank and then securing them together by pressing the said bolster blank in dies.

3. That improvement in the art of forming and securing bolsters to cutlery implements which consists in separately forming a flat blade having a perforated shank and central projection therefrom, a separately formed round bolster blank, having a grooved neck, a transversely slotted head and a central round hole extending into and terminating within the slot of the said head, assembling the said parts with the perforated shank within the said slotted head and the central projection therefrom in the said round hole, and then securing the parts together by changing the round form of the bolster blank into an oval form, forcing the metal thereof into the perforation of the said shank and the opposite walls of the slotted head firmly together at points outside the opposite edges of the said shank by pressing the said bolster blank in dies.

4. That improvement in the art of forming and securing bolsters to cutlery implements which consists in separately forming a flat blade having a shank with a central projection therefrom, a separately formed round tang having a holding shoulder near one end, and a round bolster blank having a slotted head and a round hole extended from the other end of the said bolster blank to and terminating within the slotted portion of the said head, assembling the said parts with the said shank within and filling the middle portion of the said slotted head while the central projection therefrom enters the said round hole, and with the shouldered end of the said round tang within the round hole of the said bolster blank, and then pressing the said blank in dies and forcing the metal thereof solidly over the opposite edges of the shank and solidly into engagement with the shouldered portion of the said tang.

5. A bolster blank for use in the art of securing bolsters to separately formed cutlery implements which consists of a separate single piece of the general contour of

the finished bolster, the same having a blade receiving head at one end, the said head having a slot of uniform width from end to end and extended transversely through the said head with a substantial depth at the opposite open ends thereof, and having also a central tang receiving aperture that opens

into the said slot and is extended to the opposite end of the said piece.
